US0D1101486S

(12) **United States Design Patent** (10) **Patent No.:** **US D1,101,486 S**
(45) **Date of Patent:** **** Nov. 11, 2025**

(54) **CONNECTOR OF PACKAGING FOR FOODSTUFFS**

(71) Applicant: **Botrista, Inc.**, Dover, DE (US)

(72) Inventors: **Wu-Chou Kuo**, Taipei (TW); **Yu-Min Lee**, New Taipei (TW)

(73) Assignee: **BOTRISTA, INC.**, Dover, DE (US)

(**) Term: **15 Years**

(21) Appl. No.: **29/937,780**

(22) Filed: **Apr. 17, 2024**

(57) **CLAIM**

The ornamental design for a connector of packaging for foodstuffs, as shown and described.

DESCRIPTION

FIG. 1 is a top, front, right side perspective view of a connector of packaging for foodstuffs, showing the new design;

FIG. 2 is a front view thereof;

FIG. 3 is a rear view thereof;

FIG. 4 is a left side thereof;

FIG. 5 is a right side view thereof;

FIG. 6 is a top view thereof;

FIG. 7 is a bottom thereof; and,

FIG. 8 is a bottom, rear, left side perspective view thereof. Features shown in broken lines in the drawings form no part of the claimed design.

1 Claim, 8 Drawing Sheets
